(57) **CLAIM**

The ornamental design for a trailer having a multiplicity of solar panels which can be arranged in a group of four solar panels on a trailer and can be expanded to a group of eight solar panels on a trailer, as shown and described.

DESCRIPTION

FIG. 1 is a side perspective view of the trailer having a multiplicity of solar panels which can be arranged in a group of four solar panels on a trailer and can be expanded to a group of eight solar panels on a trailer, having four solar panels exposed and the remaining four solar panels in the retracted condition showing my design;

FIG. 2 is a top plan view thereof;

FIG. 3 is a front view thereof;

FIG. 4 is a right side view thereof;

FIG. 5 is a rear view thereof;

FIG. 6 is a left side view thereof;

FIG. 7 is a side perspective view of the trailer with all eight solar panels in the expanded condition;

FIG. 8 is a top plan view thereof;

FIG. 9 is a front view;

FIG. 10 is a right side view;

FIG. 11 is a rear view; and,

FIG. 12 is a left side view.

In the drawings, the broken lines in FIGS. 1 and 7 depict wheels and axles, and the broken lines in FIGS. 5 and 11 depict door handles and form no part of the claimed design.
